US00D829627S

(12) **United States Design Patent** (10) **Patent No.:** **US D829,627 S**
(45) **Date of Patent:** **** Oct. 2, 2018**

(54) **WHEEL**

(71) Applicant: **DEKA Products Limited Partnership**,
Manchester, NH (US)

(72) Inventors: **William Daniel Hunt**, Gilmanton, NH
(US); **Jason Michael Overton**,
Manchester, NH (US)

(73) Assignee: **DEKA Products Limited Partnership**,
Manchester, NH (US)

(**) Term: **15 Years**

(21) Appl. No.: **29/592,452**

(22) Filed: **Jan. 30, 2017**

(51) LOC (11) Cl. **12-16**

(52) U.S. Cl.

USPC **D12/204**
